UNITED STATES PATENT OFFICE

2,446,424

HAIR DRESSING DEVICE

Elizabeth L. Kline, Memphis, Tenn.

Application November 7, 1946, Serial No. 708,287

1 Claim. (Cl. 132—34)

1 This invention relates to devices for dressing hair and particularly relates to a device for use in forming so-called pin curls.

In the hair dressing art the designs of waves and curls are varied by the operators in accordance with the customer's desires. These designs frequently include a plurality of individual curls and ringlets formed of the hair and the most frequent mode of forming these individual curls has heretofore been by winding the customer's hair by hand about a spool or other tool, commencing the wind from the ends of the hair and winding inwardly toward the scalp of the customer. This mode of forming curls has developed one serious disadvantage in that by beginning the wind at the outer end of the hair, uncurled and frizzled ends have been left, producing at times an undesired distortion of the hair design.

Heretofore pin curls were formed by the operator first combing, by hand, a lock of the customer's hair, then applying a wave setting liquid and finally rolling the hair about a circular object, such as the operator's finger or the like. The rolled curl is then pinned in place and allowed to dry.

Upon drying the formed curl is unrolled, recombed and formed into the desired hair style. This recombing is very tedious for if snarls are allowed to form, the curl becomes distorted and often produces wave sets of irregular patterns. Then too, should no snarls be encountered while recombing it is only because the operator has been very exacting in her work, which requires considerable time, to say nothing of the discomfort rendered the customer while waiting for the completed operation.

The reason of snarls developing in the hair by the hand wound method is that the curl is formed by working from the hair ends inward, then upon the letting out of the curl the hair ends cannot all be gathered at once, since the hair ends are lying on the inside of the formed curl. Thus when the hair is let out some of the hair ends entangle with adjacent hair to form a snarl. These snarls then have to be picked out "piece-meal" and extreme care given not to stretch or distort the curl.

The principal object of this invention is to provide a device for forming individual curls in hair in which the winding of the curls is begun at the scalp and the lock of hair is wrapped around the device, the wrapping progressing toward the ends of the hair.

A further object of the invention is to pro-

vide means for mechanically effecting such winding.

A further object of the invention is to provide a hair winding device including a relatively stationary post and a rotatable comb-like section for effecting winding of the hair about the post.

And a further object of the invention is to generally improve the design, utility and efficiency of hair curling devices.

The means by which the foregoing and other objects are accomplished and the manner of their accomplishment will be readily understood from the following specification upon reference to the accompanying drawings, in which:

Fig. 1 is a longitudinal side elevational view on an enlarged scale of the device of this invention.

Fig. 2 is a longitudinal side view partly in section and partly in elevation.

Fig. 3 is a sectional view on the line III—III of Fig. 2.

Fig. 4 is a plan view of the comb-like section used with the device; and

Fig. 5 is an end view of the comb section.

Referring now to the drawings in which the various parts are indicated by numerals:

11 is the casing housing the motor by which the drive of the device is accomplished. Carried by the casing is a field 13 which is preferably rigidly secured thereto. Mounted centrally in and extending through and beyond the casing is a relatively elongated cylindrical post 15 which is rigidly secured to the base of the casing. Carried by the post 15 are bearings 17 including ball bearings 19. Secured to the casing, preferably as by welding, are thrust bearings 21, 23 facing the bearings 17 and including the multiple ball bearings 25, 27.

40 Mounted between the bearings is a rotatable hollow post 29 surrounding the fixed post 15, the hollow post being formed with beads 31, 33, these beads complementing the bearings 17, 21 and 23 so as to receive the ball bearing 19 within the bead and to have the ball bearings 25, 27 oppositely contact the sides of the bead so that the hollow post is freely rotatable between the bearings and by its formation is retained in position within the casing and around the fixed post.

50 Secured to and carried by the hollow post within the casing is an armature winding 35, the post-carried armature and the casing-carried field comprising the motor of the device, connection to the source of electric power being preferably had through a cable 37 and control of the

operation of the motor being effected through a switch 39, the switch being shown as for operation of a reversible motor whereby to selectively effect rotation of the hollow post, either in a clockwise or counter-clockwise direction as desired.

External the casing 11 an arcuate comb-like section 41 is secured to the hollow post 29, preferably by a hinge 43. The comb-like section is provided with teeth 45, 46 along both of its edges and is of arcuate shape arranged concentrically with the cylindrical fixed post 15. Preferably the comb-like section does not extend to the end of the post section and the post section preferably has a slot 47 extending along its mid line from the end of the post to a point adjacent the hinge connection of the comb-like section to the hollow post.

In operation of the device, a lock of hair of the customer is separated and is inserted in the slot 47, the device being moved until the fixed post is adjacent the scalp of the customer. The comb-like section is lowered into position to combingly engage the lock of hair, the device is energized by the operation of the switch and the hollow post is rotated, by the motor, around the fixed post, the comb-like section being thereby moved through the hair of the customer, combing it smoothly about the fixed post, this operation being continued until the end of the lock of hair has been reached, when the rotation is cut off and the comb-like section raised about its hinge so that it is disengaged from the lock of hair and the ringlet formed in the hair moved off the fixed post and pinned into position on the customer's head.

While it is preferable to provide the fixed post 15 with the slot 47 it will be understood that the slot may be omitted without departing herefrom.

It will be seen that by providing the reversible motor and the comb-like section with teeth on either side the device is enabled to operate to form either left hand or right hand wound ringlets in the same manner.

I claim:

A device for use in dressing locks of hair, comprising a casing, a fixed post rigidly secured within said casing and projecting therebeyond, a hollow post rotatably mounted on said fixed post and extending from within said casing along said fixed post a minor distance external said casing, means for rotating said hollow post about said fixed post, and a semi-circular comb section, hingedly secured to said hollow post for rotation therewith about said fixed post, said section being normally spaced from said fixed post and being provided with a plurality of comb teeth projecting therefrom along the opposite sides thereof, said teeth adapted to combingly contact a said lock of hair to smoothly wind it about said fixed post, said rotating means being reversible to selectively vary the direction of said winding.
